CLAIM

The ornamental design for a collapsible eating utensil, as shown and described.

DESCRIPTION

FIG. 1 is an isometric front, top and first side view of the collapsible eating utensil showing our new design in an extended “use” configuration;

FIG. 2 is a top plan view thereof;

FIG. 3 is a bottom plan view thereof;

FIG. 4 is an orthographic first side view thereof, both sides being the same;

FIG. 5 is an orthographic front view thereof;

FIG. 6 is an orthographic rear view thereof;

FIG. 7 is a top plan view thereof, similar to that of FIG. 2, showing our new design in a collapsed “storage” configuration; and,

FIG. 8 is an isometric front, top and first side view thereof, similar to that of FIG. 1 showing the handle locking mechanism disengaged from the fork/spoon portion and moved partially along the handle, and showing the handle pivoted approximately 90 degrees counter-clockwise relative to the fork/spoon portion and partially moved into the collapsed “storage” configuration shown in FIG. 7.
